Daniel A. Dickinson,
INVENTOR, BY
Charles H. Woodward, Atty.

UNITED STATES PATENT OFFICE.

DANIEL A. DICKINSON, OF ST. PAUL, MINNESOTA.

STEAM-BOILER.

SPECIFICATION forming part of Letters Patent No. 390,461, dated October 2, 1888.

Application filed January 17, 1888. Serial No. 261,040. (No model.)

To all whom it may concern:

Be it known that I, DANIEL A. DICKINSON, a citizen of the United States, residing at St. Paul, in the county of Ramsey and State of Minnesota, have invented certain new and useful Improvements in Steam-Boilers, of which the following is a specification.

This invention relates to sectional steam-boilers, and more particularly to that class employed in connection with steam-heating apparatus; and it consists in the construction of the independent generating-chambers, whereby the circulation of the water is maintained and the generation of the steam accelerated, as hereinafter shown and described, and specifically pointed out in the claims.

This invention is an improvement on Patent No. 356,103, granted to me January 18, 1887.

In the drawings, Figure 1 is a sectional elevation. Fig. 2 is a plan view in cross-section on the line X X of Fig. 1. Fig. 3 is an enlarged plan view of one of the sectional generating-chambers detached. Fig. 4 is a sectional view on the line Y Y of Fig. 3.

A represents the walls or casing, which may be of any material or form of construction, but which will generally be of brick, and in which the furnace and boiler are embedded, as shown.

B represents the fire-pot, which will be formed in independent hollow sections, as shown, forming, when placed in position, the fire-pot of the furnace.

From each of the fire-pot sections a branch pipe, a, leads upward and is connected to a branch, b', projecting downward from hollow segmental sections C, as shown, the series of sections equaling in number the sections of the fire-pot, and when placed in position, as shown in Figs. 1 and 2, the sections form a series of flat hollow disks. The lowermost set of these sections C, when in position, are substantially in contact with each other, but do not quite reach the inner surface of the inclosing-wall A, while the next set of sections above are in contact at their outer rims with the interior surface of the surrounding walls, but are not in contact at their centers, leaving openings d through the center of each alternate disk formed by the sections, so that the products of the combustion arising from the fire-pot are caused to take a "zigzag" course through and around the sections and

come in contact with every part, and also with the main generating-chamber D above them. The separate sections composing the disks are not united to each other, but the sections are united perpendicularly by branches b', having flanges b'', by which they are bolted or otherwise fastened together.

If preferred, each of the disks composed of the sections may be cast in one piece. The upper set of the sections C are similarly united to the generating-chamber D, as shown. By this means the different sections of the fire-pot B, the sections C, and the generating-chamber D are all united, while at the same time the fire-pot sections and the generator are still further united by connecting-tubes E, embedded in the brick-work A, as shown.

Within each of the branches b', and also passing through each of the sections C, between the branches b', is a tube, b³, somewhat smaller than the branches b', and having an auxiliary branch or conduit, b⁴, connected to it and leading outward into and with its end opening into the interior of the sections near their outer rims. The generating-chamber D also has a series of internal tubes, b⁵, one for each of the tubes b³, and adapted to rest opposite the latter when in position, as shown in Fig. 1.

The ends of all the tubes b³ are adapted to be in contact when the branches b' are united by the flanges b'', so that together they form a continuous tube within the branches b', as shown, these auxiliary tubes b³, with their branches b⁴, insuring a perfect, rapid, and free circulation throughout all the interiors of all of sections C, thereby preventing the formation and accumulation of steam at any one point more than another, and also preventing the burning of any of the parts by reason of the failure of the water to freely circulate thereon.

The steam generating in the several sections will pass up to the chamber D through the large branches or pipes b', while the water is returned from the chamber D to the generating-sections C through the auxiliary tubes b³ b⁴ b⁵. The lower surfaces of the sections C will be formed inclining downward and inward toward the branches b' from all directions, so that the proper drainage will be insured, and the outer rims of each of the sections will be

enlarged, as shown at *e*, so as to provide for an increased space for the circulation. Each of the sections *C* forming the smaller disks will be made precisely alike, and each of the 5 sections *C* forming the larger disks will be formed precisely alike, so that the sections are interchangeable, thus greatly simplifying the construction and the repairing and replacing of parts. Each section with its branches 10 and auxiliary circulating-pipes will generally be formed in one piece, as shown in Figs. 3 and 4, thereby greatly simplifying the construction and requiring fewer joints to connect the parts, although if found desirable for 15 purpose of construction the auxiliary pipes may be made separately and set in sockets prepared for them.

Having thus described my invention, what I claim as new is—

20 1. In a steam-generator, alternating horizontal circular disks and annular disks formed of a series of hollow segmental sections, *C*, united by branches *b'* and having circulating

internal tubes, *b³*, with conduits *b⁴*, leading therefrom to the interior of the sections, whereby the circulation of the water is accelerated within and throughout said sections, substantially as and for the purpose set forth. 25

2. In a steam-generator, alternating horizontal circular disks and annular disks formed 30 of a series of hollow segmental sections, *C*, united by branches *b'*, each section and its branches having internal circulating-tubes, *b³*, and conduits *b⁴*, segmental fire-pot *B*, and generator *D*, united to said disks, substantially as 35 shown and described, whereby a free and rapid circulation of the water is maintained and the generation of the steam accelerated.

In testimony whereof I have hereunto set my hand in the presence of two subscribing witnesses. 40

DANIEL A. DICKINSON.
